ELMER D. DUNNING, OF PHILADELPHIA, PENNSYLVANIA.

PUMP.

Application filed February 26, 1924. Serial No. 695,147.

My present invention relates to force pumps for fluids, particularly gas or air compression pumps. One common use is compressing air for pneumatic tires and another is compressing gas for refrigerators. Various features of the invention may be embodied in pumps having a single piston head, but they are shown herein as employed in connection with a double pump comprising two piston heads rigidly connected by a web and reciprocated in oppositely aligned cylinders by a special form of scotch yoke driving means consisting of an eccentric fitted between the adjacent bases of the piston heads and acting alternately on one and then on the other to force the compression strokes of each, the suction strokes being accomplished by traction through the web connection between the piston heads.

One object of the invention is to provide a rugged, practically unbreakable construction in which the operating parts have extremely large bearing surfaces, and another object is to provide for automatic force feed lubrication of said surfaces. Another feature is providing a relatively massive crank shaft and arranging it so that it may be mounted between bearings at both ends of the shaft and which can be removed and replaced in operative position within the device through an opening which is but little larger than the diameter of the eccentric.

The above and other features of my invention may be more readily understood from the following description in connection with the accompanying drawings, in which

Fig. 1 is a side elevation, partly broken away to longitudinal vertical section;

Fig. 2 is a vertical transverse section substantially along the broken line 2, 2, Fig. 1, but showing the shaft and eccentric in side elevation;

Fig. 3 is a plan view showing the stationary parts in horizontal section and the moving parts in plan;

Fig. 4 is a detail side elevation of the drive shaft and eccentric;

Figs. 5 and 6 are respectively side and end elevations of the bronze slide bearings for the eccentric;

Fig. 7 is a side elevation of the double headed piston and web;

Fig. 8 is a section on the line 8, 8, Fig. 7;

Fig. 9 is a detail vertical section of the lubricating pump plunger;

Fig. 10 is a longitudinal section of a mod-

ified form of pump with the piston and eccentric shown in elevation;

Fig. 11 is a detail showing one of the main bearings in horizontal section, with the drive shaft eccentric bearing and double headed piston in operating relation.

The embodiment shown in Figs. 1-9 inclusive is connected up as a two-cylinder compression pump, but it will be obvious that by other connections it may be made a two-cylinder vacuum pump, or it may both vacuumize and compress; or, if desired, it may be connected up as a two-stage compressor or vacuumizer, or both. In any of these cases, the more important elements and their operation will be as follows:

Piston heads 1, 2 having piston rings 3, 3, 4, 4, are connected base to base by web 5, 5, provided with strengthening ribs 6, 6. These piston heads reciprocate in opposite axially aligned cylinders 7, 8, having heat radiating ribs 9, 9. These cylinders are preferably cast integral with the base 10, which is formed as an oil reservoir of ample capacity.

The driving means for the piston includes shaft 11, which is preferably integral with eccentric 12, which is provided with a collar 13. The integral extension 11^a is somewhat smaller than shaft 11, for a purpose to be described.

Encircling the eccentric 12 is a bronze collar 14, formed with bearing surfaces 15, 15, accurately fitting against and sliding upon surfaces 16, 16 of the piston heads.

The main bearing 20 for shaft 11 is in a removable closure block having a very wide bearing surface in the lateral opening 22 midway between the cylinders. The size of this opening is slightly greater than the diameter of the eccentric 12, and is in fact just the right size to be a loose fit for the collar 13.

The shaft extension 11^a is journalled in a bushing 24 screwing into the opposite side of the cylinder casting, in alignment with the main bearing 20.

The above parts are assembled by inserting the double headed piston through an open end of one of the pump cylinders. The bronze bearing collar 14 is then fitted on the eccentric 12 snugly against collar 13. The shaft eccentric and collar are inserted through opening 22, with slide surfaces 15, 15, in contact with the wear surfaces 16, 16 of the piston. The bushing 24 for the shaft

extension 11^a and the main bearing block 21 for shaft 11 are moved axially into their operative positions, bearing 24 being held by its screw thread and 21 being held by suitable bolts 25, 25. The inner end of the bearing 20 maintains the eccentric collar 13 snugly engaging the bronze bearing ring 14, forcing the latter against the vertical face of web pieces 5, 5 of the piston.

10 Preferably the bearing 24 extends through the slot between webs 5, 5 into end engagement with eccentric 12. In such case, the slot has to be wider than the diameter of the bearing, and in such case the bronze collar 14 may be provided with vertical extensions 14^a, 14^a, thus making it possible to have a desired latitude for vertical movement of the slide without danger of the upper or lower edges of the collar catching 20 in said slot of the piston.

15 It will be obvious that the slide surfaces 15 and the internal surface 14 bearing upon the large diameter eccentric 12, are well adapted to distribute all of the operating pressures over a relatively great surface and require minimum lubrication. However, I find that the practical operating conditions and wear and tear of compressors of this kind makes it desirable to have most 30 copious lubrication. For this purpose I drill lengthwise of the shaft a main oil duct 30, having at least three branches, branch 31 leading to the bearing surface of the shaft within the bearing 24, the branch 32 35 leading to the wear surface of the eccentric, and the branch 33 leading to the wear surface of the main bearing. The duct 30 being drilled in from the end of the shaft, is kept copiously supplied with oil by a reservoir 40 in bathing relation thereto. This reservoir is shown as a cavity in the casting 40 closed by plate 41 secured by screws 42.

45 While it is possible to make this cavity large enough and deep enough for more or less effective gravity feed of the oil, I prefer to employ a force pump for keeping the reservoir full and also for maintaining a predetermined pressure of the oil causing a forced feed through duct 30 and its 50 branches. Such a pump is represented by pump piston 50, reciprocating in cylinder barrel 51, communicating at the bottom through opening 52 with the base reservoir 10, and having its top portion extending 55 into reservoir 40, in operative relation to any suitable eccentric surface carried by the drive shaft 11, or 11^a. In the specific form shown, this eccentric surface is in the form of a pin 53 on a screw plug 54, screwing axially into the end of shaft 11^a. This plug 60 is formed with an oil duct 55 communicating with the duct 30 in the shaft. Piston 50 has an internal passage 57, the bottom thereof being enlarged and fitted with a 65 check valve 58, forced downwardly by a

spring 59 and the upper outlet 60 discharging into reservoir 40. The spring 61 beneath the piston forces it normally upward into contact with a suitable eccentric surface or element on the drive shaft, in this case, a 70 pin 53, by which the piston is depressed once for every revolution of the drive shaft.

75 In practice this depressing movement is extremely rapid and escape of the oil from beneath the piston being very slow by reason of its inertia and viscosity, each depression of the pump plunger causes oil to flow in past check valve 58 and out through 80 60 into the reservoir 40. At the end of the down stroke valve 58 closes automatically and under normal conditions the spring 61 85 returns the piston to the upper position, ready for another depression stroke. It will be noted, however, that when the reservoir 40 becomes full and sufficient back pressure accumulates, the spring 61 will not be able to force a full up-stroke of the piston. Consequently, as the pressure increases the 90 strokes will become shorter and shorter, the pump being thus automatically self regulating to maintain a forced feed the pressure of which is dependent on the strength of spring 61, the viscosity of the oil and the piston areas.

95 The ends of the pump cylinders are closed in by heads 70, 71, screwed to integral cylinder flanges 72, 72 by bolts 73, 73. In the present case the cylinder heads are shown as covering also the outlet ducts 75, 75 leading to the discharge outlet 76. The air 100 passages and the valves are in these heads. In each case there is an inlet 80 leading to a valve cavity 81 covered by plate 82. The check valve comprises the stem 83, disk head 84, thrust washer 85, held by pin 86, whereby the thrust of spring 87 is applied to maintain the inlet valve 84 normally closed. The outlet valve 90 is slidably mounted in valve plug 91 and normally closed by spring 92. 105 The valve chamber 93 communicates through 110 passage 94 with the outlet 75 above referred to.

115 In Fig. 10, the moving parts are all substantially the same except that the valves and connections are those of a two-stage pump. In this case the large low pressure piston 1^a operates to force partially compressed air or gas through pipe 75^a to inlet valve 84^a of a smaller high compression piston 2^a, whence the discharge of the doubly compressed air or gas is through outlet 100.

120 I claim:

1. A double pump, including a straight bore casting forming opposed cylinders with an integral case between them; a web connected double-headed piston having opposed slide surfaces transversely mounted in rigid relation on the rear faces of the heads and a longitudinally slotted guide surface on the rigid connecting portion at right angles to

- said transverse slide surfaces; a cooperating drive shaft, eccentric and bearing collar with the side face of the eccentric adjacent said longitudinal guide surface; and long bearing supports for the shaft on opposite sides of the eccentric, one bearing extending through the slot of the guide surface of the piston and both extending approximately to the eccentric.
- 10 2. A double pump, including a straight bore casting forming opposed cylinders with an integral case between them; a web connected double-headed piston having opposed slide surfaces transversely mounted in rigid relation on the rear faces of the heads and a longitudinally slotted guide surface on the rigid connecting portion at right angles to said transverse slide surfaces; a cooperating drive shaft, eccentric and bearing collar with the side face of the eccentric against said longitudinal guide surface; and long bearing supports for the shaft on opposite sides of the eccentric, one bearing being carried by an endwise removable closure fitted within 20 a lateral opening in the pump casing which opening is but slightly larger than the eccentric, and the other bearing being carried by an endwise removable member screw-threaded within an opening in the opposite side of the pump casing, which opening is of sufficient diameter to permit angular shifting of the shaft and withdrawal of the eccentric through the opposite opening when said closures are removed.
- 25 3. A pump comprising cylinder, piston and a scotch yoke drive therefor, including a drive shaft supported in two outside bearings and carrying between the bearings an eccentric, the parts being formed with an oil duct drilled straight through from one end of the shaft and having branches for discharging oil through the shaft to both its bearings and to the periphery of the eccentric, said latter branch opening through a portion of the eccentric remote from the maximum pressure dead center thereof.
- 40 4. A pump comprising cylinder, piston and a scotch yoke drive therefor, including a drive shaft supported in two outside bearings and carrying between the bearings an eccentric, the parts being formed with an oil duct drilled straight through from one end of the shaft and having branches for discharging oil through the shaft to both its bearings and to the periphery of the eccentric, said latter branch opening through a portion of the eccentric remote from dead center points thereof.
- 45 5. A pump comprising cylinder, crank case, piston and a scotch yoke drive therefor, including a drive shaft supported in two outside bearings and carrying between the bearings an eccentric, the parts being formed with an oil duct from one end of the shaft and having branches for discharging oil through the shaft to both its bearings and to the periphery of the eccentric, in combination with an oil chamber in the bearings of one of said shafts and in bathing relation to the entrance end of said oil duct, a pump having its intake in communication with the drainage space in the crank case and its outlet in said oil chamber, the piston of the pump extending adjacent the drive shaft and an eccentric element on the latter for direct drive of the piston.
- 50 6. In a double pump, two opposed cylinders and a connecting crank case in which oil drains by gravity; a web-connected, double-headed piston; a scotch yoke drive therefor, including an eccentric and integral drive shaft having an oil duct leading to a portion of the periphery of the eccentric which is remote from dead center points thereof; an oil chamber connected with the entrance end of said duct; a pump having its intake in communication with the drainage space and its outlet in said oil chamber and means on the drive shaft for operating the pump.
- 55 7. In a double pump, two opposed cylinders and a connecting crank case in which oil drains by gravity; a web-connected, double-headed piston; a scotch yoke drive therefor, including an eccentric and integral drive shaft formed with oil ducts leading to the periphery of the eccentric and to the main bearings; an oil chamber in one of said main bearings connected with the entrance of said duct; a pump having its intake in communication with the drainage space in the crank case and its outlet in said oil chamber and means on the drive shaft for operating the pump.
- 60 8. A pump comprising a cylinder, crank case and piston, and, in combination therewith, a scotch yoke drive element, including yoke slide surfaces transversely mounted in rigid relation on the rear of the piston and a longitudinal guide surface at right angles to said slide surfaces and a cooperating drive shaft and eccentric, the side face of the eccentric fitting against said longitudinal guide surface to prevent axial rotation of the piston; a non-rotating bearing collar fitting on the periphery of the eccentric and having slide surfaces engaging the transverse slide surfaces of the yoke; and means for holding said collar in position, including an annular flange on the eccentric, a thrust bearing to hold the face of the eccentric in contact with the longitudinal guide surface on the piston, with the slide collar clamped between the latter and said flange on the eccentric.
- 65 9. A pump comprising opposed cylinders and an intermediate crank case, and a web-connected, double-headed piston, and, in combination therewith, scotch yoke drive elements, including plane slide surfaces trans-

versely mounted in rigid relation on the rear of the respective piston heads and a longitudinal slide surface at right angles to said yoke surfaces on the web connection; a co-operating drive shaft and eccentric, the side face of the eccentric fitting against said longitudinal guide surface to prevent axial rotation of the piston and a non-rotating bearing collar fitting on the periphery of the eccentric and having slide surfaces engaging the transverse slide surfaces of the heads; and means for holding said collar in position, including an annular flange on the eccentric, a thrust bearing to hold the face of the eccentric in contact with the longitudinal guide surface on the web and with the slide collar clamped between the latter and said flange on the eccentric.

10. A pump comprising opposed cylinders and an intermediate crank case, a web-connected, double-headed piston, the rear faces of the piston heads being formed with opposite, plane bearing surfaces extending transversely to the axis of the piston, and said web being formed with a longitudinal guide surface with a longitudinal slot there-through, in combination with a scotch yoke drive therefor, including a drive shaft extending through said longitudinal slot in the web and an eccentric on the drive shaft having a side face fitting against said longitudinal guide surface of the web to prevent axial rotation of the piston; and a non-rotating bearing collar fitting on the periphery of the eccentric and formed with plane slide surfaces engaging the transverse slide surfaces of the head and having a lateral slide surface engaging the longitudinal slide surface of the web.

40. 11. A pump comprising opposed cylinders and an intermediate crank case, a web-con-

nected, double-headed piston, the rear faces of the piston heads being formed with opposite, plane bearing surfaces extending transversely to the axis of the piston, and said web being formed with a longitudinal guide surface with a longitudinal slot, in combination with a scotch yoke drive therefor, including a drive shaft extending through said longitudinal slot in the web and an eccentric on the drive shaft having a side face fitting against said longitudinal guide surface of the web to prevent axial rotation of the piston; and a non-rotating bearing collar fitting on the periphery of the eccentric and formed with plane slide surfaces engaging the transverse slide surfaces of the head and having a lateral slide surface engaging the longitudinal slide surface of the web; said collar being also formed with radial extension members affording extension slide surfaces at right angles to the slot through the web, adapted to bridge the slot when said collar is in the extreme upper or lower position.

12. In a pump, the combination of a cylinder, a piston, a drive shaft casing, a drive shaft in said casing, an eccentric on said drive shaft, guiding extensions on said piston and extending across the drive shaft adjacent one side of the eccentric, and bearings for said shaft extending from the outside of the casing approximately to the eccentric and having opposed end thrust bearing surfaces for fixing the plane of rotation of the eccentric, one of said bearings being in an endwise removable screw bushing and extending between the guiding extensions.

Signed at New York, in the county of New York, and State of New York, this 25th day of February, A. D. 1924.

ELMER D. DUNNING.
